Specification for Design.

Patented Oct. 26, 1915.

Application filed July 9, 1915. Serial No. 39,006. Term of patent 14 years.

To all whom it may concern:

Be it known that I, WILLIAM B. REED, a citizen of the United States, and a resident of Westfield, in the county of Hampden, State of Massachusetts, have invented a new, original, and ornamental Design for a Radiator-Section, of which the following is a specification, reference being had to the accompanying drawings, forming part thereof.

In the drawings Figure 1 is a side view showing the contour of one surface of a

radiator section. Fig. 2 is a side view showing the contour of the opposite face of a radiator section. Fig. 3 is a plan view showing the contour of the faces of a radiator section.

I claim—

The ornamental design for a radiator section as shown.
